UNITED STATES PATENT OFFICE.

CHARLES WIRT, OF PHILADELPHIA, PENNSYLVANIA.

ELECTRIC-LIGHTING APPARATUS.

1,314,295.

Specification of Letters Patent. Patented Aug. 26, 1919.

Application filed January 3, 1917, Serial No. 140,355. Renewed January 16, 1919. Serial No. 271,512.

To all whom it may concern:

Be it known that I, CHARLES WIRT, a citizen of the United States, residing in the city of Philadelphia, county of Philadelphia, 5 State of Pennsylvania, have invented certain new and useful Improvements in Electric-Lighting Apparatus, of which the following is a specification.

This invention relates to improvements in 10 incandescent lamp sockets having means for varying the amount of current traversing the lamp. The objects I have in view are to improve the appearance of the device, cheapen the construction, increase the factor 15 of safety, reduce the size, and improve certain details of construction.

These and further objects will more fully appear from the following specification and accompanying drawings, considered together 20 or separately.

In the drawings

Figure 1 is a longitudinal sectional view of a device embodying my invention.

Fig. 2 is a sectional view of the same, 25 taken on the line 2—2 of Fig. 1.

Fig. 3 is a sectional view of the same, taken on the line 3—3 of Fig. 1.

Fig. 4 is a sectional view of the same, taken on the line 4—4 of Fig. 1.

30 Fig. 5 is a perspective view of the rotary switch member.

Fig. 6 is a sectional view through the hollow resistance element, on a reduced scale, taken on the line 6—6 of Fig. 1.

35 Fig. 7 is a diagrammatic view of the circuits, and

Fig. 8 is a diagrammatic view of the resistance conductor and contact members.

In all these views like parts are design- 40 nated by the same reference character.

Referring to the drawing the incandescent lamp *a* has a base *b* forming one terminal and another terminal *c*. This is the ordinary Edison base. In the embodiment chosen 45 to illustrate my invention this base enters a shell 1. This shell is preferably made of sheet metal and is provided with screw threads for engagement with the corresponding threads on the base of the lamp.

50 It is to be understood if the base of the lamp is of different shape the characteristics of the shell will be modified accordingly. Associated with this shell is a hollow resistance element 2. This hollow resistance ele- 55 ment is cup-shaped, and surrounds the shell and also the base of the lamp, and by over-

lapping in this manner the length of the fixture is reduced. The hollow resistance element is in the form of a hollow cylinder having relatively thick walls and having one end closed. A resistance conductor 3 is supported in the annular wall of the element 2. This is shown to be in the form of a metal wire wound, preferably spirally, in any number of layers and embedded in a suitable supporting and insulating material. Associated with this resistance conductor are a number of contact members, electrically connected to the conductor at different points. In the embodiment chosen for illustration, these contact members are four in number and are designated by the characters 4, 5, 6 and 7. In the embodiment chosen for illustration the contact member 4 is electrically connected to the shell 1, the contact member 7 is electrically connected to one extremity of the conductor 3, the other contact members 5 and 6 are connected intermediate the ends of the conductor. These contact members are also 60 embedded in the wall of the element and extend upward to the top thereof so as to be engaged by the switch member, about to be described, and convey current to the lamp through varying lengths of the resistance 65 conductor as depends upon the particular contact member at the moment in electrical engagement with the switch member. Associated with the hollow resistance element 2 is a block 8. This block is preferably made 70 of insulating material, for example, porcelain molded in suitable shape. This block is mechanically connected to the hollow resistance element by a standard 9. In the embodiment chosen for illustration, this standard is in the form of a metal bolt so as to make mechanical and electrical connections through different elements of the device. Under the head of this standard, and between the said head and the closed end 75 of the hollow, cylindrical resistance element 2, is an insulating washer 10 so that the standard is electrically insulated from the shell 1 while its head is adapted to electrically connect with the lamp terminal *c*.

Associated with the parts previously described is a switch member 11. This switch member is adapted to convey current, as depends upon its position, to any one of the contact members 4, 5, 6 or 7, or to neither 80 of them if the lamp is to be extinguished. It has an insulating body 12 formed of any

- suitable material, for example, porcelain. It also has a contact element 13, preferably made of spring metal, so as to elastically engage with the upper end of the hollow resistance element and brush along the exposed upper ends of the contact members so as to make a suitable electric circuit. The switch member is moved preferably in a rotary direction by suitable means 14, for example, 5 a chain or cord, made in two pieces, each attached to an opposite side of the switch member, so that by pulling upon either piece the switch member will be rotated in the desired direction and to the desired extent.
- 10 15 In connection with the parts already described there is a leading-in terminal 15 electrically connected to the standard 9, so that the current will flow thence to the lamp terminal c, and a second leading-in terminal 20 16 electrically connected to the rotary switch member 11 so that the current will flow thence to the contact members and resistance conductor 3 to the shell 1 and lamp base b.
- 25 The details of construction which I prefer to employ are as follows:
- The shell 1 is provided with a suitable locking element 17 to prevent rotation of the shell in the hollow resistance element. This locking element 17 may be in the form 30 of a projection as shown.
- Referring more particularly to Figs. 1, 2 and 6, illustrating the hollow resistance element, it will be seen that the resistance conductor is embedded in a suitable insulating 35 body 18. Any suitable material may be used for this purpose which will possess sufficient mechanical strength and insulating properties and at the same time properly take care of the heat generated in the resistance conductor. The resistance element is provided 40 with an outer casing 19 and an inner casing 20. With suitable insulating materials these casings may be omitted. It is also apparent that the shell 1 may be integrally combined 45 with the hollow resistance element. In the embodiment chosen for illustration however the inner casing 20 is formed of metal and is electrically connected with the contact member 4, see Fig. 1. One extremity of the 50 resistance conductor 3 is also connected with this contact member, so that when the contact element 13 is in the position shown in Fig. 1, the current will flow directly through the contact member 4 to the casing 20 and thence to the shell 1, and to the base of the lamp. When the contact element 13 engages 55 successively with the contact members 5, 6 and 7 due to the movement of the switch member, the current will flow through the 60 appropriate contact member and through a varying amount of the resistance conductor, thus interposing a resistance which depends upon the position of the switch member and varying the amount of current passing 65 through the lamp and the brilliancy thereof.

correspondingly. The inner casing 20 is provided with a suitable locking element 21 to engage with the locking element 17 on the shell 1. In the embodiment chosen for illustration this locking element as shown 70 is a depression formed in the inner casing 20. The hollow resistance element in the embodiment chosen for illustration is shown substantially of cylindrical shape with a closed upper part. The upper part of the 75 resistance element as shown has an opening therein for passage of the standard 9 and the size of this opening may be varied as desired.

The block 8 has an annular rim 22 which 80 encircles and incloses the switch member. As shown in the embodiment chosen for illustration, this annular rim mechanically engages with the upper edge of the hollow resistance element, and is held in contact therewith by means of the standard 9. The block is provided with a recess 23 on the end opposite the annular rim. It is also provided with a recess 24, on one side. The recess 23 is adapted to contain a mechanical and electrical connection with the standard 9 while the recess 24 is adapted to contain an electrical connection from the leading-in terminal 16 to the switch member.

The standard 9 has an enlarged head 25, 95 provided with a suitable notch for application of a screw driver or other tool. This head engages with a counter-sunk washer 26, so as to increase the extent of bearing surface upon the insulating washer 10. The 100 other end of the standard is provided with screw threads 27. These screw threads engage with screw threads formed in a plate 28 lying within the recess 23 and forming a part of the leading-in terminal 15.

The switch member is adapted to be mounted upon and rotate around a cylindrical bushing 29. This bushing is preferably made of metal and extends from the block 8, to the base or closed end of the 110 hollow resistance element 2. The bushing is provided with a flange 30 at one end thereof, and said flange rests upon the base of the resistance element. The purpose of the spacer is to keep the switch member a 115 sufficient distance away from the hollow resistance element, so that the contact element 13 may elastically engage with the contact members. A suitable plate 31, of annular shape, is located within the recess 24. 120 The opening of this plate surrounds the boss 32 on the block 8, said boss being of circular shape and preferably extending into the bushing 29 and centering the latter. This annular plate 31 is electrically connected with the leading-in terminal 16, preferably by having a screw threaded opening therein with which the binding post constituting the leading-in terminal engages. The switch member preferably has a peripheral 130

flange 33 made integral with the insulating body 12. Associated with this flange is a flanged ring 34 forming a channel for containing the actuating means 14. A suitable recess 35, formed in the insulating body 12, is adapted to be engaged by a projection 36 formed in the flanged ring and by means of which it is retained in position on the body. On opposite sides of the flanged ring, are 10 openings 37, preferably made by slitting or cutting the material on three sides and bending outwardly a flap 38. Lying within each opening is a keeper 39 formed in U or staple shape, with a slot for passage of the chain 15 and with wings lying inside of the flanged ring and also within recesses 40 formed in the insulating body 12. If the actuating means 14 be made of a chain similar to that illustrated, a spherical member of the chain 20 may lie inside of the keeper, the stem of such member passing through the slot in the keeper. This will form a connection having sufficient flexibility for practical purposes. The contact element 13 is preferably integrally formed in connection with a washer 25 14 formed of elastic electric conductive material. This washer, in the embodiment chosen for illustration, is provided with two integral flaps or arms one forming the contact element 13 and the other a spring 30 which will bear upon the element 2. The two flaps will support the switch member on the element while permitting it to rotate relatively thereto. It is also provided with 35 a suitable locking element engaging with the insulating body 12. In the embodiment chosen for illustration, the locking element is formed by punching the material forming the washer into a recess in the bottom of the 40 insulating body 12. A suitable washer 43 is on the other side of the insulating body 12 and the two washers 41 and 43 are connected together by a flanged sleeve 44. Preferably the washer 43 and flanged 45 sleeve 44 are made of electrically conductive material so that the current may flow from the annular plate 31 to the contact element 13, through the washer and flanged sleeve, as well as through the bushing 29.

50 On one side of the block 8 is a guide 45 for the actuating means 14. Preferably this guide is formed of metal of trumpet shape. It is preferably held in position by means of a screw 46. This screw also carries a 55 stop 47, see Figs. 1 and 4. This stop lies within the path of the keepers 39, and defines and limits the movement of the switch member 11. The guide 45 also is provided with a projection 48, engaging in a recess 60 49 in the outer casing 19 of the hollow resistance element 2 to prevent the latter from rotating.

The parts already described may be 65 closed in an outer shell preferably formed of metal in two parts. The upper part or

casing 50 is adapted to inclose the upper end of the lower part or casing 51. To connect the two parts or casings together suitable locking plates 52 are employed, see Fig. 2. Each plate is provided with projecting flanges at both ends. The flange at the lower end engages with an annular recess 53 formed on the lower casing 51. The upper end of the plate passes through an opening in the upper casing 50 and engages with the side of such opening. A suitable locking screw 54 passes through a screw threaded opening in the locking plate and holds the latter in engagement with the upper end of the lower casing 51, engaging the flange on 80 the bottom end of the locking plate with the annular recess 53, and also engaging the flange on the upper end of the locking plate with the opening in the upper casing 50. This forms a connection possessing sufficient 85 strength to support the lower casing 51. Within the upper casing is a suitable insulating lining 55. On the upper part of the upper casing 50 is a suitable supporting thimble 56. The lower casing 51 may carry 90 supporting means for a canopy or shade as shown.

It will be seen from the preceding description that the hollow resistance element surrounding the shell 1 reduces the length of 95 the device, and by locating the switch member within the socket formed by the flange 20 of the block 8, which flange engages the top of the hollow resistance element, the moving parts, i. e., the switch member 100 and its connections, are inclosed by the insulating material of the block and the closed end of the resistance element are protected from injury, are hidden from sight, and any sparking that may occur will be 105 inside of the cavity formed by the block and the closed end of the resistance element, thus increasing the factor of safety.

The closed end of the resistance element provides for a complete separation of the 110 cavity in which the switch member 11 is located from the cavity of the element 2. The use of a separate spacer between the block and the element is avoided. The block and element are rigidly secured together and the socket 1 has a rigid connection with the cup-shaped element.

As before stated the shell 19 may be omitted if desired. The shell 20 may likewise be omitted, in which case the projections 17 of the socket 1 may engage the depressions in the closed end of the element. If desired the socket 1 may define the bore of the element 2 and be molded in the element. In this situation the projections may, if desired, be omitted and the engagement of the material of the element with the outside of the threads of the socket be relied upon to secure the socket in position. The contact member 4 will be secured directly 120 125 130

to the socket 1. The annular end plate forming the top of the socket, as viewed in Fig. 1, may be omitted, together with the washers 10 and 26, and the head 25 of the bolt 9 may engage directly with the closed end of the element 2.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

15 Having thus described my invention what I now claim as new and desire to secure by Letters Patent, is—

1. A lamp socket comprising an immovable hollow resistance element, one end of said element being closed, means for supporting the base of an incandescent electric lamp within the element, an insulating member rotatable relatively to said element, and means carried by said member for cutting different amounts of resistance in circuit with said lamp.

2. A lamp socket comprising an immovable hollow resistance element, one end of said element being closed, means for supporting the base of an incandescent electric lamp within the element, an insulating member carried by and rotatable relatively to said element, and means carried by said member for cutting different amounts of resistance in circuit with said lamp.

3. A lamp socket comprising an immovable cup-shaped resistance element adapted to surround the base of an incandescent electric lamp, said resistance element containing a resistance, a rotatable switch member of insulating material carried on the base of said element, and means carried by said switch member for connecting electrically different portions of said resistance conductor in circuit through the lamp.

4. A lamp socket comprising an immovable cup-shaped resistance element, means for supporting the base of an incandescent electric lamp within said element, a rotatable switch member of insulating material associated with said hollow resistance member, the base of the element being disposed between the lamp and the switch member, and means for varying the amount of resistance in said hollow resistance element in circuit with the lamp.

5. A lamp socket comprising a shell for engagement with the base terminal of the lamp, a cup-shaped resistance element surrounding the shell and immovable in relation thereto, said resistance element having a resistance conductor electrically connected with the shell, means for electrically connecting said resistance conductor at points intermediate its ends, a rotary switch mem-

ber of insulating material associated with said resistance element, and means associated with said switch member for conducting current through said resistance conductor at different points thereof.

6. A lamp socket comprising a shell for engagement with the base terminal of the lamp, a cup-shaped resistance element surrounding the shell and immovable in relation thereto, said resistance element having a resistance conductor electrically connected with the shell, a plurality of contact members electrically connected with different parts of the resistance conductor, a rotary switch member of insulating material supported on the base of the said resistance element, and having a contact element adapted to engage with different contact members as it is rotated, means for rotating the switch member, an electrical connection with the shell, and an electrical connection with the switch member.

7. A lamp socket comprising a shell for engagement with the base of a lamp, a cup-shaped resistance element surrounding the shell and immovable in relation thereto, said resistance element having a resistance conductor electrically connected with the shell, a plurality of contact members electrically connected with different parts of the resistance conductor, a block carried by the element, a standard electrically insulated from the shell and adapted to electrically contact with the other terminal of the lamp, said standard mechanically connecting the resistance element immovably in relation to the block, a rotary switch member surrounding the standard and electrically insulated therefrom, and with a contact element adapted to engage with different contact members of the resistance element as it is rotated, means for rotating the switch member, a leading-in terminal in electrical connection with the standard, and a stationary leading-in terminal electrical connection with the switch member.

8. A lamp socket comprising an immovable, cupped element of insulating material adapted to surround the base of an incandescent electric lamp, said element containing a resistance, a switch member supported by the element, and means carried by said switch member for electrically connecting different portions of said resistance in circuit through the lamp.

9. A lamp socket comprising an immovable, cupped element of insulating material adapted to surround the base of an incandescent electric lamp, said element containing a resistance, a rotatable switch member supported by the element, and means carried by said switch member for electrically connecting different portions of said resistance in circuit through the lamp.

10. A lamp socket comprising an immov-

- able, cupped element of insulating material adapted to surround the base of an incandescent electric lamp, said element containing a resistance, a rotatable switch member 5 of insulating material supported by the element, and means carried by said switch member for electrically connecting different portions of said resistance in circuit through the lamp.
- 10 11. A lamp socket comprising an immovable, hollow element of insulating material, adapted to surround an incandescent electric lamp, one end of said element being closed to form a base, a resistance device embedded 15 in the element, contact members secured to the resistance device at separated points, said contact members extending through the base of the element, a rotatable switch member of insulating material supported on the 20 base of the element, means carried by the switch member for rotating the same relatively to the element, and means carried by the switch member for electrically connecting different portions of the resistance in 25 circuit through the lamp.
12. A lamp socket comprising an immovable hollow resistance element, one end of said element being closed to form a cup, a resistance device embedded in the element, 30 contact members engaging the resistance device at separated points, means within the cup of the element for supporting the base of an incandescent electric lamp, a block, said block having an annular flange engaging the element, there being a cavity formed 35 between the block and the closed end of the element, a rotatable insulating member within the cavity, means carried by said member for cutting different amounts of resistance in circuit with the lamp, and means for rotating the member.
13. A lamp socket comprising an immovable cup-shaped resistance element having a resistance device embedded in its wall, contact members engaging the resistance device 45 at separated points, means within the cup for supporting the base of an incandescent electric lamp, a block having an annular flange, said flange engaging the closed end 50 of the cup thereby forming an inclosed cavity between the cup and block, a standard for securing the block and cup together, a tubular column positioned between the block and cup and within the cavity and surrounding the standard, an insulating switch member disposed within the cavity and rotatable about the column, a spring finger carried by the switch member and adapted to coat with a contact member whereby varying 55 amounts of resistance may be cut in circuit with the lamp as the switch member is rotated, and means for rotating the switch member.
14. A lamp socket comprising an immovable cup-shaped resistance element, a re- 60
- sistance device embedded in the element, means within the cup for supporting the base of an incandescent electric lamp, a block of insulating material, said block having an annular flange extending axially 70 thereof, said flange engaging the resistance element, means for securing the block and element together, there being a cavity inclosed by the block and the closed end of the element, a rotatable switch member of insulating material in the cavity, means carried by the switch member for contacting with the resistance device, means for rotating the switch member, a leading-in terminal in 75 electrical connection with the switch member, and a leading-in terminal in electrical connection with the lamp base.
15. A lamp socket comprising a shell for engagement with the base of a lamp, a hollow resistance element surrounding the shell 80 and immovable in relation thereto, said resistance element having a resistance conductor electrically connected with the shell, a plurality of contact members electrically connected with different parts of the resistance 85 conductor, a block, a standard electrically insulated from the shell and adapted to electrically contact with the other terminal of the lamp, said standard mechanically connecting the resistance element in immovable relation to the block, a rotary switch member surrounding the standard and electrically insulated therefrom and with a contact element adapted to engage with different contact members as it is rotated, means for rotating the switch member, means for limiting the movement of the rotary switch member, a leading-in terminal in electrical connection with the standard, and a stationary 90 leading-in terminal in electrical connection 95 with the stationary switch member.
16. A lamp socket comprising a shell for engagement with the base of a lamp, a hollow resistance element surrounding the shell and fixed in relation thereto, said resistance 100 element having a resistance conductor electrically connected with the shell, a plurality of contact members electrically connected with different parts of the resistance conductor, a block, a standard electrically insulated from the shell and adapted to electrically contact with the other terminal of the lamp, said standard mechanically connecting the resistance element and the block, a rotary switch member surrounding the 105 standard and electrically insulated therefrom and with a contact element adapted to engage with different contact members as it is rotated, means for rotating the switch member, a stop carried by the block, a leading-in terminal in electrical connection with the standard, and a leading-in terminal in 110 electrical connection with the switch member.
17. A lamp socket comprising a shell for engagement with the base of a lamp, a hol- 115

- low resistance element surrounding the shell and fixed in relation thereto, said resistance element having a resistance conductor electrically connected with the shell, a plurality of contact members electrically connected with different parts of the resistance conductor, a block, a boss on the block, a bushing engaging the boss, a standard electrically insulated from the shell and adapted 5 to electrically contact with the other terminal of the lamp, said standard mechanically connecting the resistance element and the block, a rotary switch member carried by the bushing and surrounding the standard and electrically insulated therefrom and with a contact element adapted to engage 40 with different contact members as it is rotated, means for rotating the switch member, a leading-in terminal in electrical connection with the standard, and a leading-in terminal in electrical connection with the 45 bushing.
10. A lamp socket comprising an inclosing shell, a fixed, hollow, cylindrical insulating element within the shell, a support for an incandescent electric lamp supported 50 within and in immovable contact with the element, a spiral resistance embedded in the element, a rotatable cylindrical switch member of insulating material in axial alignment with the element, a spring contact carried by the switch member for electrically connecting different portions of the resistance conductor in circuit with the lamp support, a spring carried by the switch member and engaging the element, means for rotating the switch member, and means insulated from the switch member for limiting the 55 rotation of the switch member.
15. A lamp socket comprising a shell for engagement with the base of a lamp, a hollow resistance element surrounding the shell and fixed in relation thereto, said resistance element having a resistance conductor electrically connected with the shell, a plurality of contact members electrically connected 60 with different parts of the resistance conductor, a block, a boss on the block, a bushing engaging the boss, a standard electrically insulated from the shell and adapted to electrically contact with the other terminal of the lamp, said standard mechanically 65
20. to 25. (Continuation of claim 10)
25. A lamp socket comprising an inclosing shell, a fixed, hollow, cylindrical insulating element within the shell, a support for an incandescent electric lamp supported 70 within and in immovable contact with the element, a spiral resistance embedded in the element, a rotatable cylindrical switch member of insulating material in axial alignment with the element, a spring contact carried by the switch member for electrically connecting different portions of the resistance conductor in circuit with the lamp support, a spring carried by the switch member and engaging the element, means for rotating the switch member, and means insulated from the switch member for limiting the 75 rotation of the switch member.
30. A lamp socket comprising a shell for engagement with the base of a lamp, a hollow resistance element surrounding the shell and fixed in relation thereto, said resistance element having a resistance conductor electrically connected with the shell, a plurality of contact members electrically connected 80 with different parts of the resistance conductor, a block, a boss on the block, a bushing engaging the boss, a standard electrically insulated from the shell and adapted to electrically contact with the other terminal of the lamp, said standard mechanically 85
